ABSTRACT OF THE DISCLOSURE

A percussion mechanism in a breech loading gun where a percussion hammer is engaged with a sear which holds the hammer at full cock, where the direction of force of a preloaded spring bearing on the percussion hammer through a stirrup is closely located at the center of rotation of the percussion hammer and with the rotation of the percussion hammer in operating a trigger, the said direction of force moves away from the said center of rotation.

FIELD OF THE INVENTION

This invention relates to a percussion mechanism in a breech loading gun characterized in that it usually is actuated by a percussion hammer held in a cocked position, and in firing it releases the engagement by pulling an interlocking trigger, reducing the engagement load of a sear which allows the action of the percussion hammer, and the engagement load of said percussion hammer being as small as possible, results in a decreased force of operating the trigger and reduces the time of releasing the said engagement in order to reduce the marksmanship error and to obtain enough striking power for a firing pin to fire a percussion cap.

SUMMARY OF THE INVENTION

The idea of this invention exists in the improvement of a percussion mechanism characterised where in the engagement status of the percussion hammer with the sear, the direction of force of a spring bearing on the percussion hammer is closely located at the center of rotation of the percussion hammer and the said direction of force moves away from the said center of rotation as the percussion hammer rotates when released by operating the trigger.

BRIEF DESCRIPTION OF THE DRAWINGS

In the accompanying drawings in which the vertical sectional side views show an embodiment of the percussion mechanism of the gun in accordance with the present invention and is illustrated as follows:

FIG. 1 shows the mechanism before firing, and

FIG. 2 shows the mechanism after firing.

Referring to the drawing, a percussion hammer 2 is pivoted to be freely rotatable about a pin 2a in a breech block 1 of a breech loading gun, and its rear end 2b is in contact with a firing pin 5 fixed to a breech closure 4 by a screw bushing 3 and its front side is formed with a concave bearing 2c with which is engaged a stirrup 6b of the spring rod 6, the base 6a of which is located in

2

the bearing hole 4a of the breech block 4 and operates to rotate the percussion hammer 2 in the direction of the arrow by a spring 7 preloaded on the said spring rod 6 between the breech closure and the stirrup 6b. In the 5 lower part of the percussion hammer 2 is formed the engagement part 2d with which a sear 9 rotatably mounted on a pin 9a interlocking with a trigger 8 is engaged to maintain the cocked preparatory to firing position. Under the conditions where the direction of force of the spring 10 7 is in the operating line p' in proximity to the line p, the rotating moment of the spring 7 on the percussion hammer 2 is small. Whereas, with the rotation of the percussion hammer 2 released from the engagement, the said direction of the line of force moves away from the rotation center 2a, the rotating power of the spring 7 on the 15 percussion hammer 2 is increased.

For cocking the breech block 1 to the firing position, a hand lever 10 is turned to the right hand side, permitting the opening of the gun barrel 11 which operates a percussion 20 hammer lever 13 by means of a front base 12, said lever 13 being removably fixed to the gun barrel 11.

The percussion hammer lever 13 is rotated around a pin 13a and its percussion hammer lifting part 13b pushes up the percussion lever locking part 2d of the percussion 25 hammer 2 which pushes the spring rod 6 and compresses the spring 7 to move it to the preloaded position. At the same time the end of the sear 9 engages the locking part 2d directly in advance of the cocked position. As a result even if the gun barrel 11 is closed, the percussion 30 hammer 2 is locked by the sear 9 and holds the spring 7 in a preloaded position.

By operating the trigger 8 the sear 9 rotates about the pin 9a, releases the engagement of the sear 9 and releases the percussion hammer 2, which then rotates by means 35 of the energy of the preloaded spring 7 and the rear end 2b of the percussion hammer 2 strikes the rear of the firing pin 5 to fire the percussion cap.

According to the present invention the line of force 40 of the spring 7 is closely located to the rotation center 2a of the percussion hammer 2 under the condition of the hammer set in the cocked preparatory to firing position as stated above, so that the rotating power acting on the percussion hammer 2 is small and accordingly, the engaging 45 load at the operating time of the sear is weak, so the required force to pull the trigger is reduced and there is negligible engagement wear and engagement damage resulting in longer life of the moving parts and increased accuracy in the firing of the gun.

What is claimed is:

1. A percussion mechanism in a breech loading gun comprising
a breech blocking including a socket;
a percussion hammer;
a shaft;
said hammer mounted pivotably on said shaft;
a firing pin; said pin fixed to said breech block;
said hammer having at its forward portion a concave recess;
a spring rod, a stirrup and an activating spring; the base of said spring rod being movably and pivotably located in said socket; said stirrup engaging said concave recess in said percussion hammer;

3 an engagement nose in the lower portion of said hammer; a sear; said sear engaging said nose in the "firing preparatory position"; said spring in the "firing preparatory position" being 5 poised to move said stirrup in the direction away from the near center position of said shaft, the rear end of said hammer shaped to hit the said pin.

2. A percussion mechanism as claimed in claim 1, the end portion of said spring rod located within said socket 10 being tapered to permit limited pivotal movement of said stirrup, whereby in the firing position said stirrup and said rod are moved pivotably and forwardly to follow the arcwise movement of said recess of said percussion ham-

mer into an angular position below the center of said shaft of said hammer.
